SUPPORT FOR ROCK DRILL

Paul C. O'Leary, Salt Lake City, Utah, assignor, by mesne assignments, to Machinery Center, Inc., Salt Lake City, Utah, a corporation of Utah

Filed Nov. 26, 1958, Ser. No. 776,568

3 Claims. (Cl. 248—2)

This invention relates to rock drilling equipment, and particularly to what is known as a jumbo.

For various earth work, such as the driving of mine shafts, there has been developed drilling equipment mounting a plurality of rock drills in such a manner that they are individually operable, manually, within respective areas which extend outwardly from a support in common. Thus, one machine supports and locates a number of individual rock drills with respect to the work to be done, the rock drills being individually operated by drillers within their respective work areas. Such a machine is generally referred to as a jumbo.

Jumbos designed for mine shaft work have been unwieldy and have been capable of use only in shafts having adequate cross-sectional area to permit introduction of bulky equipment. Desired reach for the individual drills has been achieved only at the expense of compactness; the drill-supporting structure has had to be sufficiently broad to place the drills within or near the particular outskirt work areas.

A principal object of this invention is to so construct a drill jumbo as to provide for exceptional compactness when not in use, without sacrificing requisite breadth for work purposes.

Another object is to provide a drill jumbo that can be easily lowered through the hoist section of a sectional timber set in a shaft being sunk, and, after reaching the bottom, be structurally expanded so as to comprehend the cross-sectional area of the shaft and place the individual drills at the outskirts thereof for work purposes.

A feature of preferred embodiments of the invention for the accomplishment of these objects is the provision of an umbrella-style platform that mounts the individual rock drills, and the provision of mechanism for raising and lowering such platform in order to bring the equipment into working position from collapsed position and vice versa.

Additional objects and features of the invention will become apparent from the following detailed description of the presently preferred specific embodiment illustrated in the accompanying drawings as an example of how the generic inventive concepts here disclosed may be applied in practice.

In the drawings:

Fig. 1 represents a vertical section taken through a typical mine shaft being sunk with the aid of a drill jumbo conforming to the invention, the jumbo being shown in elevation and in collapsed position as it is lowered through the central, hoisting section of a conventional three-section timber set;

Fig. 2, a corresponding view showing the drill jumbo opened up into working position at the bottom of the shaft;

Fig. 3, a horizontal section taken on the line 3—3 of Fig. 1, showing the collapsed jumbo in top plan;

Fig. 4, a vertical section taken on the line 4—4 of Fig. 3 and drawn to an enlarged scale, shaft parts in the

2

background being omitted so as to show only the jumbo;

Fig. 5, a top plan view of the jumbo in the raised, working position shown by dotted lines in Fig. 4;

Fig. 6, a horizontal section taken on the line 6—6 of Fig. 4 and drawn to an enlarged scale;

Fig. 7, a fragmentary vertical section taken on the line 7—7 of Fig. 5; and

Fig. 8, a vertical section taken on the line 8—8 of Fig. 4.

10 Referring to the drawings:

In the illustrated construction, the drill jumbo comprises a central supporting post 10, divergently formed at its upper end as a housing 11 to accommodate hoist mechanism, and defining along its length a slideway 13, Figs. 4, 6, and 8.

The post 10 is conveniently fabricated from two structural steel channels 10a, Fig. 6, facing each other and secured in mutually spaced relationship by housing 11 and by a box-like base 12 to provide longitudinally extending guide slots 14 at opposite lateral sides for the reception of respective laterally extending wings 15a of a slide 15 which is fitted in slideway 13 for free sliding movement upwardly and downwardly of the post. The divergently-formed upper end 11 of post 10 is conveniently fabricated from steel plate, see Fig. 4, welded to the upper ends of channels 10a.

Hinged to respectively opposite lateral sides of the upper, housing portion 11 of post 10 are a pair of substantially rectangular platform sections 16, each of which 30 has considerably greater width than has post 10 so as to span a relatively wide work area extending transversely of such opposite lateral sides of post 10. These platform sections serve to mount universally movable jack drill assemblies 17 for extension and retraction relative thereto 35 into and out of relatively widely spaced work positions disposed laterally of such platform sections.

In the illustrated construction, the jack drill assemblies are articulately mounted on the respective platform sections 16 by means of arms 18, which are each laterally extensible and retractable relative to its platform sections by 40 means of pivotal securement 18—1 of its inner end to an inner corner of such platform sections. Latching means are provided for retaining arms 18 in retracted or extended position, as desired. In the form shown, Figs. 45 and 7, the respective latching means comprise latch bolts 19 resiliently mounted, by means of coil springs 20, in and between the spaced plates 18a, Fig. 7, of lugs 18—1, which project from arms 18, respectively. Such latching means further comprise keeper holes 21 drilled 50 or otherwise provided through and at appropriate locations in the respective platform sections 16 for receiving latch bolts 19. Latch-strings 22 hang from latch bolts 19, respectively, for convenient manipulation by the drilling crew.

Means are provided for raising the platform sections 16 into extended, working positions and for lowering them into collapsed positions. In this illustrated embodiment, such means comprise links 23 pivoted at one set of ends to wings 15a, respectively, of slide 15 by means 60 of pins 24 and pivoted at the other set of ends to the outer end portions of platform sections 16, respectively, by means of pins 25.

Such means also comprise means for raising and lowering the slide 15, which preferably constitutes mechanism housed within the post. In the preferred form illustrated, the raising and lowering mechanism is a chain hoist 26 operably mounted in housing 11, with its load chain 27, Fig. 4, hooked onto engagement member 15b of slide 15 and its hand chain 28, Fig. 8, hanging outside 65 of post 10.

For anchoring the jumbo drill in place in its extended,

working condition, hydraulic jacks 29 of standard type are secured to the platform sections 16, respectively.

In using the drill jumbo of this invention for shaft-sinking purposes, for example, the further sinking of timbered shaft 30, Figs. 1 and 2, the cable 31 of the usual shaft hoist (not shown) is attached to bail-fitting 32, the drill jumbo being in its collapsed position. In this position, such drill jumbo is sufficiently compact to be lowered through the hoist section 33 of sectional timber set 34.

When the drill jumbo reaches bottom, with its base 12 firmly seated on the earth or rock floor 30a of the shaft, Fig. 2, its platform sections 16 are raised to extended positions by manual operation of chain hoist 26, and it is firmly anchored to the shaft walls by extending the anchor jacks 29 in the usual manner. Thereafter, the drill assemblies 17 may be placed in required working position by pulling latch strings 22 and extending arms 18 as shown in Fig. 5.

Whereas this invention is here illustrated and described with respect to a presently preferred specific embodiment thereof, it should be understood that various changes may be made without departing from the essential inventive concepts.

I claim:

1. A drill jumbo for shaft work comprising a supporting post structure; a pair of substantially rectangular platform sections pivotally secured to the upper part of said post structure at opposite sides thereof, respectively, and transversely of its height so as to swing from lowered substantially vertical position to raised, substantially horizontal position and vice versa, each of said platform sections having considerably greater width than has said post structure so as to span a relatively wide work area extending transversely of said opposite sides thereof; means for raising and lowering said platform sections; drill-mounting arms pivotally secured to inner corners,

respectively, of said platform sections and extending outwardly therefrom; lugs extending from said arms, respectively, intermediate their lengths, toward and into lapping relationship with respective platform sections; cooperative latch means carried by said lugs and said platform sections, respectively, and having latching positions corresponding to inwardly retracted and outwardly extended positions of said arms; means secured to the outer ends of said arms, respectively, for mounting respective rock drills; and means for supporting said post structure in an erect position during working periods.

5 2. The drill jumbo of claim 1, wherein the post structure includes a slideway extending longitudinally thereof; and wherein the means for raising and lowering the platform sections comprises a slide operable within said slideway; links articulatively interconnecting the slide with outer end portions of the platform sections; and a manually operable, chain hoist, having its load chain attached to said slide and its hand chain hanging outside the post.

10 3. The drill jumbo of claim 1, wherein the means for supporting the post structure comprises a pair of anchor jacks mounted centrally of the platform sections, respectively, and extending transversely thereacross.
